UNITED STATES PATENT OFFICE

CHARLES LEE FITCHET, OF OAKLAND, CALIFORNIA

GLOBE SUPPORT FOR ELECTRIC LIGHTS

Application filed May 12, 1930. Serial No. 451,545.

This invention relates to supports or holders for electric light globes, and it has for its primary object to provide a simple and efficient form of globe holder which, instead of having its weight imposed on the thereby embraced lamp socket, is supported independently of said socket and without the use of attaching screws or other means requiring adjustment.

10 A further object is to structurally improve and simplify, as also to enhance the appearance of, the globe holder disclosed in my prior Patent No. 1,457,058, granted May 29, 1923.

In describing the invention in detail, reference is herein had to the accompanying drawings, in which—

Figure 1 is a top plan view of the invention, parts being shown broken away; and—

Figure 2 is a view of the same partly in side elevation and partly in vertical section.

The invention includes a support composed of two identical complementary members or sections 1, each comprising a circular horizontal body portion 2, an upwardly extending centrally located neck portion 3, and a depending peripheral skirt portion 4. Said skirt portion is contracted adjacent to its lower edge to closely embrace the neck portion 5 of the glass globe 6 which is to be supported, as shown.

Each of the two sections 1 has formed on its neck and skirt portions opposite radially directed lugs 7 and 8 which, in the assembled relation of said sections, occupy abutting relation and have directed therethrough attaching screws or bolts 9 and 10 whereby said sections are secured in rigid complementary relation.

The neck portions 3 of the sections 1 have at their upper ends integral outwardly and oppositely directed arms 11 which constitute seats whereon rest opposite inwardly directed arms 12 formed on the short vertical neck

13 of a canopy-like metal reflector 14.

45 Screws or bolts directed through the engaged

arms 11 and 12 secure said canopy in rigid relation to the support, as shown. Cords 15 or other appropriate form of suspension means serve to suspend the structure either from a ceiling outlet or from the lamp cord 50 (not shown) said cords being suitably attached, as by directing through holes 16 provided therefor in the arms 12 and by the formation in the lower ends of the cords of arm-underlying knots 17.

55 Seated in closely fitted relation to the neck 13 of the reflector 14 is the lower end of a tubular shell or chimney 18 through which pass heated currents of air rising from the interior of the globe.

60 The body portion 2 of the support sections 1 are provided with a plurality of passages 19, herein shown as having the form of slots, through which heated air from the interior of the globe is permitted to escape. Said escaping heated air creates a draft which induces cool air currents to rise between the skirt 4 of the support and a depending skirt portion 20 of the reflector 14, by which currents said heated air is promptly carried off through 65 the chimney-like shell 18.

65 The neck members 3 are provided with vertical flutes or corrugations 21, thus to permit escape of heated air between said members and the lamp socket which is embraced 70 thereby.

A bell-like finishing shell or husk 22 is 75 preferably employed, the same having its lower end resting in seated embracing relation to the upper part of the skirt 20 of the reflector, and having its upper end portion disposed in closely embracing relation to an intermediate portion of the shell 18. Interengaging beads 23 and 24 formed on said shell 18 and said upper end portion of the 80 husk 22 serve to maintain said elements against chance shifting movement from their properly assembled relation.

85 What is claimed is—

90 1. A globe support comprising a holder

composed of complemental sections detachably secured in rigid relation, said holder including a substantially horizontal apertured body portion, a circumferential depending skirt portion contracted to embrace the neck of the globe, and a neck for embracing a lamp socket; arms directed radially outward from the neck of said holder, a reflector having radial arms supported upon and attached to the arms of said holder, a chimney-like draft tube superposed on said reflector, and suspension means leading outward from said attached arms.

2. A globe support for electric lamp sockets comprising a multiple section holder in which the sections occupy rigidly attached complemental relation and have a skirt in embracing supporting relation to the neck of the globe, said holder having a neck for embracing a lamp socket, a reflector encircling said holder, said holder and said reflector having means whereby they are detachably secured in fixed relation, a chimney-like draft tube surmounting said reflector, and means for suspending said parts independently of the lamp socket.

3. A globe support for electric lamp sockets, comprising a holder composed of substantially identical complemental sections adapted for attachment in embracing relation both to a lamp socket and to the neck of the globe which is to be supported, a reflector superposed upon and encircling said holder, said holder and said reflector being relatively spaced to afford therebetween an unobstructed passage for upward circulation of air, said holder being provided with means permitting escape into said passage of air from the interior of the globe, a draft tube surmounting said reflector, and means for suspending said parts independently of the lamp socket.

4. A globe support for electric lamp sockets, comprising a holder composed of substantially identical complemental sections adapted for attachment in embracing relation both to a lamp socket and to the neck of the globe which is to be supported, a reflector superposed upon and encircling said holder, said holder and said reflector being relatively spaced to afford therebetween an unobstructed passage for upward circulation of air, said holder being provided with means permitting escape into said passage of air from the interior of the globe, a draft tube surmounting said reflector, a finishing husk mounted in embracing relation to the lower part of said tube and to the adjacent portion of said reflector, and means for suspending said elements independently of the lamp socket.

5. A globe support comprising a holder composed of complemental sections detachably secured in rigid relation, said holder including a substantially horizontal apertured body portion, a circumferential depending

skirt portion contracted to embrace the neck of the globe, and a neck for embracing a lamp socket; arms directed radially outward from the neck of said holder, a reflector having radial arms detachably mounted upon the arms of said holder, said holder and said reflector being relatively spaced to afford therebetween an unobstructed passage for upwardly directed air currents, a draft tube surmounting said reflector, and suspension means for said parts.

In testimony whereof, I affix my signature
CHARLES LEE FITCHET.
